Primary Examiner — Lakiya Rogers*Assistant Examiner* — Harold E Blackwell, II(74) *Attorney, Agent, or Firm* — Muncy, Geissler, Olds & Lowe, P.C.(57) **CLAIM**

I claim the ornamental design for a tool holder, as shown and described.

DESCRIPTION

FIG. 1 is a right, front, top perspective view of a tool holder showing my new design;

FIG. 2 is a front elevational view thereof;

FIG. 3 is a rear elevational view thereof;

FIG. 4 is a left side view thereof;

FIG. 5 is a right side view thereof;

FIG. 6 is a bottom plan view thereof;

FIG. 7 is a left, front, bottom perspective view thereof;

FIG. 8 is a left, rear, bottom perspective view thereof;

FIG. 9 is a right, rear, bottom perspective view thereof; and, FIG. 10 is a drawing showing the tool holder in use.

The top view is devoid of claimed ornamentation, and is omitted from the drawings.

The broken lines in the drawings illustrate portions of the tool holder which form no part of the claimed design.

The dot-dashed line in defines the boundary of claimed and unclaimed objects, and the dot-dashed line forms no part of the claimed design.
